United States Patent Office

Des. 179,594
Patented Jan. 29, 1957

179,594

SPOON OR SIMILAR ARTICLE

Chester Barber Crookes, Danbury, Conn., assignor to The Hobson & Botts Co., Danbury, Conn., a corporation of Connecticut.

Application July 17, 1956, Serial No. 42,273

Term of patent 14 years

(Cl. D54—12)

Fig. 1 is a front elevation of a spoon or similar article embodying my new design;

Fig. 2 is a side elevation of the same;

Fig. 3 is a section taken along the line 3—3 of Fig. 1 in the direction of the arrows;

Fig. 4 is a section taken along the line 4—4 of Fig. 1 in the direction of the arrows; and

Fig. 5 is an enlarged view of the handle element of the spoon, as shown in Fig. 1.

The back of the spoon is plain.

I claim:

The ornamental design for a spoon or similar article, substantially as shown and described.
